UNITED STATES PATENT OFFICE.

ARTHUR ALLISON, OF MAYWOOD, CALIFORNIA, ASSIGNOR TO WILLIAM W. WILSON,
OF LOS ANGELES, CALIFORNIA.

UNDERREAMER.

Application filed July 18, 1923. Serial No. 652,465.

To all whom it may concern:

Be it known that I, ARTHUR ALLISON, a citizen of the United States, residing at Maywood, in the county of Los Angeles, State of California, have invented new and useful Improvements in Underreamers, of which the following is a specification.

This invention relates to underreamers for use in well drilling. Aside from certain general objects of the invention, which include such objects as simplicity and effectiveness of construction and operation, ready removal of the cutters for sharpening or replacement, positiveness of action, etc.; I may particularly mention certain objective features of my invention.

It is a primary object of my invention, and a feature of my underreamer, that the cutters are so interlocked with each other and with the body of the underreamer, as to be held solidly and firmly upon the body against all strain to which the cutters are subjected. This interlocking feature of my underreamer is an important one, both structurally and operatively. Each of the cutters bears inwardly against the body; and each of the cutters bears outwardly against the other cutter; and by this means the two cutters are locked to each other and locked to the body. Any inward thrust upon either of the cutters is transmitted directly to the body; and any outward thrust upon either of the cutters is transmitted to the other cutter, and then, through that other cutter, transmitted directly to the body. The transmission of such strains from the cutter to the body is short and direct; the points at which the cutters are supported—interlocked with themselves and with the body—are close to the point where strain is imposed upon the cutter.

I embody these features of my invention preferably in an underreamer characterized by having a body with a lower bifurcated end; the cutters lying alongside each other (overlapping each other) in the space of the body between its forks. The expanding and contracting actions of the cutters are caused, in this specific form, by a means extending across the fork space, preferably in the form of a bolt or pin. This bolt not only performs the function of causing the expansion and contraction of the cutters, but also performs the function of structurally connecting the two forks so as to com-

bine their strengths against any lateral force exerted upon them or upon the cutters.

In my invention, as herein described, in preferred form, there are many other objects and corresponding features of construction and operation, all of which are best understood from a consideration of the following detailed description of a preferred embodiment of the invention; and, for the purposes of this description, reference is had to the accompanying drawings in which—

Fig. 1 is a longitudinal sectional view of the lower part of the underreamer, in its expanded or operative condition; Fig. 2 is a similar view showing the parts in their contracted position within the well casing; Fig. 3 is a side elevation of the lower part of the reamer; Fig. 4 is a bottom plan view with the cutters in expanded position; Fig. 5 is a similar view with the cutters contracted; Fig. 6 is a horizontal section taken on line x^6-x^6 on Fig. 1; Fig. 7 is a vertical section taken on line x^7-x^7 of Fig. 1; Figs. 8 and 9 are perspective views of the cutters; Fig. 10 is a side elevation, corresponding, in aspect and position of the parts, to Fig. 2; Fig. 11 is a horizontal section on line $x^{11}-x^{11}$ on Fig. 1; Fig. 12 is a side elevation of the lower part of the body, a portion being broken away for purposes of illustration; and Fig. 13 is a perspective of the lower end of the spring actuated mandrel which carries the cutters.

In the drawings the numeral 2 designates the body of the underreamer, which may be equipped at its upper end with any of the usual means for connection with a string of drilling tools. The body has a longitudinal bore 3 to accommodate the mandrel 4 and spring 5. Spring 5 rests upon the key 8 which extends across the body through the slot 6 and extends through a slot 7 in mandrel 4, slot 7 being of sufficient length to allow the suitable vertical motion of the mandrel. The key 8 is held in place by suitable pins 9 through the ends of the key, the pins resting in transverse slots or grooves 10 in the surface of body 2. The upper end of spring 3 bears against washer 12 beneath nut 11 screw-threaded upon the upper end of mandrel 4.

The spring and mandrel construction herein described is merely typical; any other suitable structure may be substituted for this one without altering the invention. So far

as the invention is concerned the only function of the spring mandrel is merely to raise and support the cutters.

The lower end of mandrel 4 is suitably terminated to carry the cutters. For instance, it may terminate in an eye 13 which carries a bolt 16 projecting through transverse bores 15 of the two cutters; and the eye 13 preferably fits snugly in the socket 14 and against the circular wall 14' thereof, in the cutters. The cutters are thus supported both by the fitting of eye 13 in the sockets 14 and also by the pin 16. To permit the swinging action of the cutters in contracting and expanding the upper part of the socket 14 is cut out, as indicated at 14^a (see Fig. 9) to make room for the mandrel 4 where it enters the socket.

The lower end of body 2 is forked or bifurcated, forming forks 2^a and 2^b with a fork-space between them, said fork-space extending laterally through the lower end of the body from side to side and open at the lower end. The inner faces of the forks 2^a are accurately machined to form flat, vertical opposite bearing surfaces 17^a; and the flat vertical shanks S of the cutters lie between these surfaces alongside each other, overlapping each other between the forks 2^a and 2^b, with the external surfaces S¹ of the shanks bearing against the surfaces 17^a, the internal surfaces S² of the shanks bearing against each other, and the shanks being confined laterally between two forks. On each side of the body and at each side of the fork-space, the body is machined away to provide the vertical opposite surfaces 17, which make inthrust surfaces, against which the cutters bear, as hereinafter described. This machining also forms the downwardly facing shoulder surfaces 18 which take the upward end-thrusts of the cutters.

The two forks 2^a and 2^b are structurally interconnected by a pin or bolt 19. This pin 19 has a head 19^a with a square socket hole 19', the head fitting in one of the forks against a shoulder 19^b. The other end of pin 19 carries a nut 20 fitting in recess 22; and the nut draws down against a shoulder 21. A sleeve 19^c around pin 19 acts as a spacer between the furcations 2^a and 2^b. When nut 20 is screwed down tightly the two furcations are then rigidly and strongly connected to act effectually as a single structure against any stresses tending either to move them toward or away from each other. Pin 19 preferably fits the furcations tightly. The shanks S of the two cutters are in the general form of flat rectangular blocks; and each shank is provided with a vertical slot 23 terminating in an upper offset diagonal slot 24. In the normal expanded position of the two cutters, pin 19 stands in the lower ends of slots 23; but when the cutters are moved downwardly they move inwardly

when the upper slots 24 come into register with the pin 19; the pin standing in the upper ends of slots 24 when the cutters are contracted, as shown in Fig. 2. The movements of the cutters with relation to pin 19 are controlled by the lengths and directions of these slots 23 and 24; and the slots are preferably of such shape as to provide for an abrupt expansion of the cutters upon their initial upward movement, and then to provide for a long straight upward sliding movement of the cutters in their expanded position. This provision is made for the purpose of allowing the use of relatively large bearing surfaces for the cutters and allowing the long vertical movement of the expanded cutters necessary for the engagement of the cutters with said bearing surfaces. It will be understood that the cutter expanding means herein described (the pin and slots) is merely typical and indicative of means which may be used within the broader aspects of my invention; and I do not necessarily limit myself to such means.

The lower ends of the cutter shanks are beveled away, as shown at 25; and each cutter body B is correspondingly diagonally recessed as shown at 26, each recess 26 receiving the lower diagonal edge of the other shank when the cutters are contracted; and the diagonal spaces or passages between the recess bottoms 26 and diagonal end surfaces 25 form water courses for the passage of water for keeping the cutting ends of the cutter bodies B free from accumulation of earth. When the cutters are in their collapsed position (see Fig. 2) the lower inclined surfaces 25 fit into the recesses and fit against, or close to, the surfaces 26. These inclined surfaces so interact—are placed at such angles—as to allow the free relative movements of the cutters between the positions shown in Figs. 1 and 2; and at the same time the construction allows of the proper extension of the cutter shank to put a suitable amount of metal below the lower end of slot 23 (at the point denoted 25^a in Fig. 1) for strength; and allows of the proper downward extension of the shank behind the body B to properly support the body. And, further, the interengagement of the lower diagonal edges of the shanks in the recesses ties the two cutters together laterally when the cutters are collapsed.

The detailed formation of each cutter is best shown in Figs. 8 and 9. Shank S of each cutter is in the general form of a rectangular block with the laterally and downwardly projecting body B at its outer edge. It will be noted that the body B is not centrally located upon the shank, but projects laterally from the shank more at one side than at the other; so that, when the two shanks S are in proper position overlapping each other in the bifurcated end of the

underreamer body, the cutter bodies B will be opposite each other as shown in the various views. The inner face of each cutter body B is provided with inwardly facing 5 surfaces 27 which are vertical when the cutters are expanded; and when the cutters are expanded and then moved up these surfaces 27 then bear inwardly against the lower ends of bearing surfaces 17. At the same time, 10 when the cutters are expanded, two overhanging shoulder surfaces 34, on the inner surfaces of the cutter shanks, interengage, one with the other, in such a manner as to limit the relative outward movement of the cutters. The formations of the shoulder surfaces 34 is shown in the various sectional views. When the cutters are in their upper expanded position each cutter body bears directly inwardly against bearing surfaces 17 at a point on the back side of the cutter body and close to its lower cutting end; so that any inward strain tending to crush the cutters inwardly is immediately and shortly transmitted to the body. At the same time 25 any strain which tends to spread the cutters apart is transmitted immediately to the shoulders 34 and the tendency to spread the cutters thereby opposed. Any outward strain on either cutter is immediately transmitted to the other cutter and then to the body. The interlocking of the cutters has the effect of causing the inward bearing of one cutter to form a means for resisting the outward movement of the other cutter, as 30 well as for resisting the inthrust of the cutters under an inward crushing strain. This interlocking of the cutters, in their expanded position, is a particular feature of my underreamer, and is one which makes it 35 strong and durable. In fact, the cutters are as firmly held as if they were embedded in the body itself; and, at the same time, my method of cutter interlocking does away with the necessity of cutting special ways, 40 etc. in the body and thereby provides that the body shall be left in its fullest possible strength.

When the cutters are in their expanded position their upper end surfaces 31^a shoulder up against the down thrust surfaces 18 of the underreamer body; and the up thrust of the cutters is thereby taken. Any side thrust upon the cutters is taken by the forks 2^a and 2^b. It will be noted that the 45 shanks S of the cutters fit snugly and substantially fill the space between the forks; and, the forks being rigidly connected by the bolt 19, any side thrust upon either cutter is transmitted to and borne by the forks. 50 In fact, the structurally interconnected forks and the snugly fitting shanks form an almost solid structure very strong against lateral displacement. The shanks being wide, they not only give a good lateral bearing on the body, but are also strong in a 55 lateral direction. Any displacement of the upper end of the cutter shanks is prevented not only by the interlocking of the cutter shanks (which interlock, it will be noted, extends almost throughout the whole vertical length of the cutter shanks) and by the inward bearings of the cutter bodies upon the underreamer body, but is also prevented by the upward projection of the lugs 31, on the upper ends of the shanks, into bore 3 of 60 the body, fitting preferably somewhat easily in the bore. Any inward crushing of the extreme lower ends of the cutters, tending to rotate them about their bearing faces 27 and to throw the upper ends outwardly, is 65 opposed and prevented by the upper parts of the interlocking surfaces 34; and may also be prevented by the fitting of lugs 31 in bore 3. These lugs also form stationary 70 bearings at the upper ends of the cutters to hold the full lengths of shoulders 34 in interengagement when one or both of the cutters are strained outwardly.

I may, although this is not a necessary element, form in the opposite inner faces of 75 forks 2^a and 2^b, a pair of slots 32 into which lugs 33 on the cutters are adapted to fit when the cutters are in their upper expanded positions. These lugs lock each of the cutters directly to the forks 2^a and 2^b to 80 brace the cutters against the strains of underreaming, particularly to brace the cutters against outward spreading strains; although these lugs may be also arranged to take some of the inthrust and some of the 85 upthrust.

The surfaces 30 at the upper opposite sides of the cutter bodies B may or may not have a mechanical part to play, according 90 to specific construction and arrangement. They may be placed at such an angle that they act against the lower ends of the body forks 2^a and 2^b to assist the expanding action 95 of the cutters; or they may be placed horizontally or in any other position, and have 100 no co-action with the body.

From the foregoing the operation of my underreamer will be easily understood. When the parts are lowered through the eas- 105 ing and reach its lower end, then the upward movement of the cutters causes first an outward expanding movement of the cutters, by action of slot 24 on pin 19. This outward expanding movement is then followed by a straight upward movement of 110 the cutters, during which the surfaces 27 slide upwardly into engagement with the body surfaces 17; the interlocking surfaces 34 having been thrown into engagement with 115 each other during the initial outward expansive movement of the cutters. The cutters then move upwardly until their upper ends shoulder up against the downthrust surfaces 18. In this position lugs 33 in 120 ways 32 may also receive and bear some of 125

the upthrust. In this expanded position of the cutters the parts are all solidly supported and firmly interlocked, as hereinbefore explained. When the underreamer is again drawn upwardly into the casing, the shoulders 29 striking the lower end of the casing force the cutters downwardly on the body; and when the slots 24 have reached a position opposite pin 19, then the cutters move inwardly to the position shown in Fig. 2, the surfaces 29 then bearing against the inner surface of the casing.

It will be understood that the foregoing description is given in a typical and not a limitative sense; that the underreamer here described is a typification of forms that may come within the scope of my invention as expressed in the following claims. These claims are intended to cover the features of the invention broadly and fundamentally as well as specifically and are not limited against such modifications, changes, etc., as may be made by those skilled in the art.

Having described a preferred form of my invention, I claim:

1. An underreamer comprising a body, a pair of overlapping cutters in the body, the cutters bearing inwardly against the body, and overhanging shoulders on the overlapping cutters adapted to interengage to prevent outward movement of the cutters.

2. An underreamer comprising a body bifurcated at its lower end, the body having forks extending down on opposite sides, and a pair of cutters having flat shanks fitting between the forks, the flat shanks lying side by side against each other, the body having opposite outwardly facing bearings against which the cutters bear inwardly, and the overlapping cutter shanks having on their adjacent surfaces overhanging shoulders adapted to interlock to limit the outward movement of the cutters and to hold the cutters to each other.

3. An underreamer, comprising a body bifurcated at its lower end, a pair of cutters each comprising a flat shank and a cutter body at the lower outer end of the shank laterally overhanging the shank, the shanks of the two cutters lying flatly against each other in the fork-space of the body, the underreamer body having opposite outwardly facing bearings near its lower end, the cutter bodies having inwardly facing bearings

adapted to bear inwardly against the outwardly facing bearings, and the cutter shanks having overhanging interlocking shoulders adapted to limit the outward movement of the cutters and to hold the cutters laterally together.

4. An underreamer, comprising a body bifurcated at its lower end, a pair of cutters each comprising a flat shank and a cutter body at the lower outer end of the shank laterally overhanging the shank, the shanks of the two cutters lying flatly against each other in the fork-space of the body, the underreamer body having opposite outwardly facing bearings near its lower end, the cutter bodies having inwardly facing bearings adapted to bear inwardly against the outwardly facing bearings, and the cutter shanks having overhanging interlocking shoulders adapted to limit the outward movement of the cutters and to hold the cutters laterally together, said shoulders being on the engaging surfaces of the cutter shanks and extending from point approximately opposite the inwardly facing bearings of the cutter bodies upwardly along the shanks.

5. An underreamer comprising a body bifurcated at its lower end, a pair of cutters vertically movable on the body each comprising a flat shank and a cutter body at the lower end of the shank laterally overhanging the shank, the shanks of the two cutters lying flatly against each other in the fork-space of the body, the underreamer body having opposite outwardly facing bearings near its lower end, means to cause outward expansion movement of the cutters by virtue of their upward movement, the cutter bodies having inwardly facing bearings moved against the outward facing bearings by the upward and outward movement of the cutters, the cutter shanks having interengaging shoulders moved against each other by the outward expansion movement of the cutters, and the cutter shanks having overhanging interlocking shoulders adapted to limit the outward movement of the cutters and to hold the cutters laterally together.

In witness that I claim the foregoing I have hereunto subscribed my name this 2nd day of July, 1923.

ARTHUR ALLISON.
